Theodore E. Friend.

UNITED STATES PATENT OFFICE.

THEODORE E. FRIEND, OF NORWALK, OHIO.

CARBURETER.

1,246,581.

Specification of Letters Patent. Patented Nov. 13, 1917.

Application filed June 27, 1916. Serial No. 106,248.

To all whom it may concern:

Be it known that I, THEODORE E. FRIEND, a citizen of the United States, and a resident of Norwalk, in the county of Huron and State of Ohio, have made certain new and useful Improvements in Carbureters, of which the following is a specification.

My invention relates to improvements in carbureters, and it consists in the constructions, combinations and arrangements herein described and claimed.

An object of my invention is to provide an atomizer which can be readily adapted to a carbureting device to improve the action and make it more efficient.

Another object of my invention is to combine said improved atomizer with the desirable features of my improved carbureter, Patent No. 1,180,389, whereby a more improved vaporizing or carbureting device is obtained.

The following specification and the appended claims make clear my invention in detail.

My invention is illustrated in the accompanying drawings which form a part of this specification in which—

Figure 1 is a vertical section through the device,

Fig. 2 a vertical section through the atomizing portion of the air passage of the device on an enlarged scale, and

Fig. 3 is an angular section cut through the passage-way at the center line of the jet 4 to show the cross-section of the passage-way with the trough 7 in position without the jet 4 or the adjusting needle 12.

In carrying out my invention I provide the main air passage 1, having a draft controlling valve 2 arranged in the inlet, thereof, and the manually operated throttle 3 arranged in the outlet, thereof. The fuel inlet or jet 4 protrudes a portion of the way into the air passage 1, being fitted into the boss 5, and is fed by a constant head of fuel carried in the bowl 6 by means of the float mechanism shown and well known in the art. Communicating with the fuel jet 4 and extending across the air passage 1 is arranged the trough 7, the lower portion, thereof, surrounding the jet 4 in the cavity 8, and the upper end of which is fitted into the wall of the air passage 1 for support, and the open side of which faces toward the outlet of the air passage 1. It will be seen that the cavity 8 extends just beyond the top of

the jet 4 and that the lower portion of the trough 7 is cut back to about the center for the purpose of allowing a free discharge from the jet 4. In the back side of the trough 7, in communication with the cavity 8, is the air inlet 9, which is in communication with the atmospheric side of the valve 2 by means of the secondary air passage 10 in the form of a tube, which is attached to the trough 7 by some means such as brazing. The outlet of the jet 4 is most desirably formed into a crater portion 11 into which the adjusting needle 12, having a cone shaped head, is arranged. It will be noticed that the needle 12 is crowded to the back side of the outlet 11, which allows of a crescent shaped spray from the jet 4 on the open side of the trough 7.

The above description should suffice for showing how my improved atomizing device can be applied to any carbureter or vaporizer, as well as my improved carbureter, Patent No. 1180389, to which the drawings conform. It will not be necessary to describe the details of these drawings as this has already been done in my former specification.

It will be seen that in the operation of my improved device that the velocity of the air by the trough 7 creates a partial vacuum, therein, which is communicated to the jet 4 and the air inlet 9. This induction is in addition to that static head generally realized by the depression of pressure in the air passage 1, and is more in effect at high speeds than at low speeds, increasing the range of the jet 4. The static head induced by the trough 8 combined with that of the air passage 1 is communicated to the jet 4 and the air inlet 9 in the trough 8, but the air being lighter and less restricted than the fuel, very little static head is realized at the jet 4, as it is practically all transformed into kinetic head. Thus a more efficient atomizing is effected, especially at low speeds, as no fuel is spilled over the jet 4 without being picked up and atomized.

It will also be seen that the inlet 13 to the tube 10 is arranged to receive the impact of the main air supply, which is for the purpose of accelerating the velocity through the tube 10, and thereby keeping the atomizing of the fuel in step with the air supply, thus providing a more coherent action throughout the range of operation.

It has been stated that the adjusting needle 12 is crowded to the back side of the jet outlet 11, providing a crescent shaped spray. This is for the purpose of having 5 the spray in a single sheet whereby it can be more finely mixed with the air supply of air passage 1, and to allow of a free discharge, therefrom. Furthermore, the air fed into the cavity 8 from the tube 10 is 10 discharged with high velocity outwardly around the fuel jet 4, and at an angle into the main air current, which further effects a fine grained mixture. It being understood in the art that the velocity of the air 15 past the jet 4 picks up the fuel at the orifice 11 in fine globules into the mixture.

What I claim is:

1. A carbureter for explosive engines comprising a main air passage, an air controlling valve arranged in the inlet of said main air passage, a fuel inlet to said main air passage, a trough provided at one end with a pocket, said pocket fitted to the walls of and surrounding said fuel inlet, an adjusting needle disposed in the orifice of said fuel inlet and arranged to be crowded 20

toward the back side of said orifice to provide a crescent shaped spray on the open side of said trough, an air inlet to said pocket, an auxiliary air passage connecting 30 said air inlet with the zone of pressure on the atmospheric side of said air valve, and a portion of said trough cut back adjacent to said orifice to provide an unobstructed discharge therefrom.

2. A vaporizer for explosive engines comprising a main air-passage of triangular cross-section, a fuel inlet in the form of a nozzle in the apex of a cross-section of said main air passage, a trough provided 40 at one end with a pocket, said pocket fitted to and surrounding said nozzle, an air inlet to said pocket, an auxiliary air passage extending said air inlet toward the inlet of said main air passage, and an adjusting needle disposed in the orifice of said nozzle and arranged to be crowded toward the back side of said orifice to provide a crescent shape spray on the open side of said trough.

THEODORE E. FRIEND.
